(57) CLAIM

The ornamental design for smoking article packaging, as shown and described.

DESCRIPTION

FIG. 1 is a front perspective view of the design of the present invention in a closed position;

FIG. 2 is a bottom view of the design in a closed position;

FIG. 3 is a front perspective view of the design in an open position;

FIG. 4 is a rear perspective view of the embodiment of the design in an open position;

FIG. 5 is a front perspective view of another embodiment of the design of the invention in a closed position;

FIG. 6 is a front perspective view of the embodiment of the design of FIG. 5 in an open position; and,

FIG. 7 is a rear perspective view of the embodiment of the design of FIG. 5 in an open position. The bottom view being of the second embodiment being identical to the bottom view of the embodiment of FIG. 1.
